CLAIM

The ornamental design for a medical device holding glove, as shown and described.

DESCRIPTION

FIG. 1 is a perspective view of a medical device holding glove according to the present design;

FIG. 2 is a front view thereof;

FIG. 3 is a back view thereof;

FIG. 4 is a top view thereof;

FIG. 5 is a bottom view thereof;

FIG. 6 is a right side view thereof; and,

FIG. 7 is a left side view thereof.

The broken lines in the drawings illustrate environmental structure and form no part of the claimed invention.
